UNITED STATES PATENT OFFICE.

HERBERT E. WHITE, OF YOUNGSTOWN, OHIO, ASSIGNOR TO THE GENERAL FIREPROOFING COMPANY, OF YOUNGSTOWN, OHIO, A CORPORATION OF OHIO.

EXPANDED METAL PRODUCT.

1,314,777.

Specification of Letters Patent. Patented Sept. 2, 1919.

Application filed September 10, 1913. Serial No. 789,152.

To all whom it may concern:

Be it known that I, HERBERT E. WHITE, a citizen of the United States, residing at Youngstown, in the county of Mahoning, 5 and State of Ohio, have invented certain new and useful Improvements in Expanded Metal Products, of which the following is a specification.

This invention relates to a novel and useful form of ribbed metal product possessing 10 special utility as a self-centering and reinforcing element for cementitious bodies.

To this end, the invention has in view an expanded metal ribbed structure having 15 maximum strength and stiffness, while at the same time providing effective keys for the cementitious material, and also capable of being manufactured readily and economically.

With these and other general objects in view which will be readily apparent to those familiar with expanded metal products of this character, the invention consists of the 20 novel construction, combination, and arrangement of parts hereinafter more fully described, illustrated, and claimed.

Though susceptible of structural modification in minor particulars, one practical embodiment of the invention is shown in the 25 accompanying drawings, in which—

Figure 1 is a plan view of the new product.

Fig. 2 is a cross sectional view on the line 2—2 of Fig. 1.

Fig. 3 is a plan view illustrating diagrammatically the first stage of a method of producing the product.

Fig. 4 is a cross sectional view on the line 5—5 of Fig. 3 illustrating another stage 40 in the development of the product.

Fig. 5 is a diagrammatic cross sectional view illustrating the final form of the product resulting from the operation of laterally spreading the metal sheet shown in Fig. 4.

Like reference characters designate corresponding parts in the several figures of the drawings.

In its preferable embodiment, the improved form of product claimed herein includes a metal sheet having a plurality of deeply grooved ribs, designated by the numeral 1, and open mesh expanded sections S between every pair of said ribs R. These ribs may be produced in any manner, such 55 for instance as by the process disclosed in

my former Patent No. 1,056,871, dated March 25, 1913, and may be of any depth or height, and all of the ribs of the sheet may be of the same or different depths without affecting the distinguishing features of the 60 present invention. Also, it may be understood that the ribs R represent the non-contractible unslotted areas or strips of the product, and therefore may be grooved or not, and it is between every pair of such 65 areas that the sheet is provided with an open mesh expanded section S wherein the component strands s stand substantially on edge. That is to say, the strands of the meshes between any two uncut areas or ribs 70 of the sheet turn to positions which are inclined or oblique to the horizontal plane of the sheet, and moreover involve the distinct and novel feature of all of the strands between any two ribs or uncut areas being 75 inclined in the same direction and lying in substantially parallel oblique planes, and at the same time being reversely disposed to the inclination of the strands in the expanded section at the opposite side of one of 80 said ribs. It will be observed that the meshes formed by the strands s are substantially diamond-shape, and are disposed longitudinally of the uncut areas or ribs, said strands being integrally joined to each 85 other by uncut connecting webs w at spaced points.

In order to compensate for the non-contractibility of the uncut areas or ribs, it is necessary to elongate the metal in the 90 individual strands at the time of displacing them from the slit or cut in the sheet, thereby enabling the operation of opening the slits to be uniformly carried out without imposing undue strains on the strands at 95 any point.

One method of producing an expanded structure possessing the characteristic of having all of the strands between any two ribs set obliquely in parallel planes and having an inclination all in the same direction, is indicated diagrammatically in Figs. 3, 4, and 5 of the drawings. Referring first to Fig. 3 of the drawings, it will be observed that the blank sheet which may be preliminarily formed with a series of ribs R, and flat intervening areas f, is subjected to the action of a slitting and expanding machine, such as generally disclosed in my former Patent No. 1,049,632, dated Jan. 7, 110

1913. This machine subjects the metal sheet to an operation which makes separate lines of interrupted longitudinal slits $a-a$, $b-b$, $c-c$, $d-d$, $e-e$, etcetera, arranged alternately in 5 adjacent lines, and simultaneously displacing or offsetting to one side of the plane of the original sheet the individual strands of metal formed by the slits. Also, as indicated, in the combined slitting and expanding 10 operation, a desirable and necessary feature is the elongating of the metal in the strands.

It will be observed in the first place that the slitting and expanding operation is carried on simultaneously upon both sides of 15 every alternate uncut area or rib, so that such uncut area or rib, connecting with the expanded web upon both sides thereof, is moved with such web to one side of the 20 original plane of the sheet, taking the form of a substantially V-shaped arch as diagrammatically shown in Fig. 4 of the drawings with the uncut area or rib at the center of said arch.

25 When the combined slitting, expanding, and deforming step is completed for every unit consisting of three uncut areas or ribs and the intervening areas, the sheet is subjected to an operation which laterally spreads the same to bring the deflected uncut areas or ribs back into substantially their original plane, and to move the strands connecting therewith into substantially the 30 original plane of the sheet. This is diagrammatically shown in Fig. 5 of the draw- 35

ings. During this operation, the strands of each expanded section move into substantially parallel planes, so that each of the meshed strands between any two uncut areas or ribs maintain an inclination in the 40 same direction.

I claim:

1. An expanded sheet metal product, comprising a plurality of parallel uncut longitudinal strips coextensive in length with 45 their length in the original blank, and expanded sections of material between and connecting the strips and also coextensive in length with the length of the original blank, said expanded sections consisting of connected strands of elongated metal, and all of the elongated strands between any two uncut strips having an inclination in the 50 same direction.

2. An expanded sheet metal product including a plurality of spaced high ribs, and expanded sections between the ribs consisting of elongated connected strands arranged to form meshes of a diamond form, 55 all of the strands between any two ribs having an inclination in the same direction, but reversely inclined to the inclination of the strands at the opposite side of one of 60 said ribs.

In testimony whereof I hereunto affix my 65 signature in the presence of two witnesses.

HERBERT E. WHITE.
